COUNTER TOP COOKING UNIT OR THE LIKE

Reeves Brown, Cleveland, Tenn., assignor to Hardwick
Stove Company, Cleveland, Tenn., a corporation of Delaware

Filed Feb. 14, 1961, Ser. No. 63,938

Term of patent 14 years

(Cl. D81—25)

FIG. 2 is a cross-sectional view on the line 2—2 of FIG. 1, in the direction of the arrows, with the grates and control knobs omitted for convenience of illustration.

I claim:

The ornamental design for a counter top cooking unit or the like, substantially as shown.
